UNITED STATES PATENT OFFICE.

WILFRED BAKER, OF ABERDEEN, SOUTH DAKOTA, ASSIGNOR OF TWO-FIFTHS TO JAMES MCCABE, OF MINNEAPOLIS, MINNESOTA, AND TWO-FIFTHS TO FRANK CRANE, OF CUMMINGS, NORTH DAKOTA.

LOADING APPARATUS.

No. 910,446.

Specification of Letters Patent.

Patented Jan. 19, 1909.

Application filed July 26, 1907. Serial No. 385,707.

To all whom it may concern:

Be it known that I, WILFRED BAKER, a citizen of the United States, residing at Aberdeen, in the county of Brown and State 5 of South Dakota, have invented a new and useful Loading Apparatus, of which the following is a specification.

This invention relates to loading devices of that general class in which a wagon is 10 provided with a box or receptacle and has at the front end a fork arranged to gather up shocks, hay, fodder or the like, and toss the same into the box or receptacle without stopping the travel of the wagon.

One of the principal objects of the invention is to provide an improved form of fork operating mechanism in which the lifting power is at the maximum at the starting 20 of the lifting movement, and in which the speed of travel of the fork gradually increases toward the limit of discharging movement to insure rapidity of operation and to more effectively toss the shock or other material backward into the receptacle.

A further object of the invention is to provide an improved fork operating mechanism which may be readily controlled by the driver or other attendant and which is so arranged as to be automatically disconnected 30 when the fork has reached the limit of its discharging movement, so that danger of breakage or strain of the parts is prevented.

A still further object of the invention is 35 to simplify and improve the construction and arrangement of the machine, in order that the latter may be more readily controlled by the operator and to place the steering fork actuating and braking means 40 in such manner as to be most convenient for the operator.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the 45 form, proportions, size and minor details of the structure may be made without departing from the spirit or sacrificing any of the advantages of the invention.

In the accompanying drawings:—Figure 58 1 is a side elevation of a loading device con-

structed and arranged in accordance with the invention. Fig. 2 is a plan view of the same. Fig. 3 is a longitudinal sectional view of the apparatus showing the fork near the completion of its load discharging movement. 60 Fig. 4 is a detail view, partly in section, of a portion of the fork operating mechanism. Fig. 5 is a side elevation of the same showing a portion of the frame in section. Fig. 6 is a detail plan view illustrating a portion 65 of the automatic disconnecting mechanism. Fig. 7 is a detail view illustrating a slight modification. Fig. 8 is a detail perspective view showing the connections for automatically releasing the clutch when the fork is 70 elevated.

Similar numerals of reference are employed to indicate corresponding parts throughout the several figures of the drawings.

The main frame comprises sills or bars 10 which are connected at their rear ends by a cross bar 11, and at an approximately central point by a cross bar 12, and suitable braces 13 may be added for the purpose 80 of strengthening and bracing the structure. Near the rear end of the frame are journal boxes for the support of a rear axle 15 on which are secured wheels 16, and at the front of the frame are arranged vertical 85 casings 17 in which are mounted vertical spindles 18, the lower ends of which are turned outward to form journals for the support of the front wheels 19. The spindles are provided with rearwardly extending 90 rocker arms 20 that are connected by a link 21, and extending from this link is an arm 22 carrying a double foot rest 23 that is arranged immediately in front of and below the operator's seat 24. By exerting 95 pressure on the foot rest the vehicle may be steered in any desired course. The braces 13 which form a part of the frame are preferably arranged to extend from the cross bar or brace 12 to the lower ends of the casings 17, these casings having suitably inclined sockets 26 for the reception of the outer ends of the brace members.

The load receptacle or box 29 is hinged at 30 to the rear cross bar 11, the point of 105 connection being somewhat to the rear of the longitudinal center of the box, so that the latter may normally rest in a horizontal position on the frame, and it may be locked in this position by a suitable hook 31 piv- 110

oted to the forward end of the box and arranged to engage a pin or lug 32 that is carried by the cross bar 12. At the lower rear end of the box or receptacle is a cross plate or board 33 that is inclined approximately at an angle of 45° to the bottom of the receptacle, and which will rest practically flat on the ground when the receptacle is moved to dumping position, as shown by dotted lines in Fig. 3. Above this cross plate or board is an end gate 34 that is carried at each side of the receptacle by a pair of links 37 and 38, the links being connected together by a pin 39, and the link 38 being pivoted to a pin 40 at the side of the receptacle. The upper forward end of the link 37 is connected by a chain or cable 41 to a fixed eye or pin 42 at the lower forward end of the receptacle, said chain or cable passing over a guiding sheave 42 that is carried by a bracket 44 on one of the frame bars 10. As a result of this construction, the tilting upward of the front end of the receptacle during the dumping operation will operate through the chain or cable 41 and the links to move the end gate to open position.

Secured to the lower edges of the frame bars 10 are blocks 50 through which extend bolts 51 forming pivotal supports for the rear carrying bar 52 of a rake 53. The rake is provided with forwardly projecting arms 54 which are connected by a cross bar 55 to the ends of which are attached lifting cables 56, there being one of such cables at each side of the rake. At a point slightly in advance of the forward end of the receptacle the frame 10 is provided with a pair of standards 60 which are securely held in place, and the upper ends of which are rigidly connected by a tube 61. Through this tube extends a shaft 62 that is provided near its opposite ends with peripherally grooved snails 63, the outer ends of which are reinforced by side links 64. To the inner rings of the snails are attached the ends of the lifting cables 56, and as the snails are turned, the cables are wound thereon with gradually increasing speed, so that the lifting movement of the fork progresses at gradually increased speed from the load receiving to load discharging position.

Mounted loosely on one end of the shaft 62 is a sprocket wheel 65, and the adjacent faces of the sprocket wheel and snail hub are provided with clutching teeth 66, provision being made for moving the sprocket wheel to snail engaging and releasing position. The cables 56 are guided around suitable sheaves 67 that are carried by vertical posts or standards 68 extending upward from the frame 10, and these are preferably reinforced by brace bars 69 that extend, also, to the posts 60.

Connected to the shaft 15 by means of compensating gearing 70 is a gear wheel 71

which intermeshes with a pinion 72 that is carried by a stud shaft mounted in a short bracket 73 extending from one side of the frame. This shaft, also, carries a sprocket wheel 74 that is connected to the sprocket wheel 65 by a link belt 75 and said link belt is held in engagement with the sprocket wheel 74 by a small idler 76, so that the sprocket wheel 65 will be continuously rotated so long as the loading apparatus is driven forward. The outer portion of the hub of sprocket wheel 65 is provided with an annular groove that receives a fork 78, and said fork is connected to the rocker arm 79 on the upper end of an approximately vertical shaft 80. The upper portion of this shaft is guided through a strap 81 that is fulcrumed on the end of the shaft 62, and its lower end is guided by a bracket 82 that projects from one of the standards 60. The lower end of the shaft 80 carries a crank arm 83 from which extends a link 84, and from said link extends a second link 85 (Fig. 6) that projects beyond the inner edge of the frame bar 10 and is disposed in the path of movement of an arm 85' on the rake, so that as the latter nears the completion of its load discharging movement the arm will engage the link and transmit movement through the crank 83, the shaft 80, rocker arm 79, and fork 78 to the sprocket wheel 65, thereby moving the sprocket wheel from engagement with the snail and automatically unclutching the fork operating mechanism.

The link 84 is connected by a link 88 to a hand lever 89 that is fulcrumed on a bracket 90 within convenient reach of the operator, so that the latter may readily clutch the sprocket wheel to the snail, whenever it is desired to discharge the load received by the fork.

The inner hub of one of the snails 63 is in the form of a friction drum or disk 90' that is encircled by a band brake 91 (Fig. 5). One end of the band brake is connected to a vertically disposed rod 92 that is guided by upper and lower brackets 93-94, and between the lower bracket and a collar 95 on the rod is arranged a helical compression spring 96 that tends to normally hold the brake in release position. The lower end of the rod is connected to a crank 97 that is carried by a shaft 98 journaled in a bracket or hanger 99 carried by one of the frame members 10. This shaft extends inward and to its inner end is secured a lever 100 having an approximately horizontal arm 101 that fits against the back of the operator, so that the latter by leaning backward may apply the brake in order to check the movement of the fork. Secured to the fork is a pair of spring arms 102, which, at the completion of the upward movement of the fork come into contact with the tube 61 and check the movement without arresting the move-

ment of the shock or other load, so that the latter will be tossed rearward into the receptacle. In order to assist the return movement of the fork, the cross bar 52 is provided with a rearwardly extending arm 103 to which is connected the forward end of a spring 104. The rear end of the spring is connected by a cable or chain 105 to the cross bar 11.

10 10 A modification of the means for transmitting movement from the rear wheel shaft is shown in Fig. 7. In this case the wheel 71' is in the nature of a sprocket wheel, and the link belt 75' engages directly therewith and 15 is held against the lower portion of the sprocket wheel by suitable idlers 107.

It will be seen that the operating portion 20 of the fork is of a width approximately equal to that of the receptacle, while the carrying portion of the fork is comparatively narrow. This permits the location of the seat inside the frame so that the fork may be swung to and fro over the seat.

I claim:—

25 1. In loading apparatus, a wheeled vehicle, a pivoted fork at the front of the vehicle, a grooved snail, a cable or like member extending from the fork to the snail, a shaft carrying the snail, and driving connections between one of the vehicle wheels and the shaft.

2. In loading apparatus, a wheeled vehicle, a fork pivoted to the front of the vehicle, a peripherally grooved snail, a cable 35 extending from the fork to the snail, a shaft carrying said snail, a driven member loosely mounted on the shaft and receiving motion from one of the vehicle wheels, and means for clutching and unclutching said driven member to the shaft.

3. In loading apparatus, a wheeled vehicle, a pivoted fork at the front of the vehicle, a peripherally grooved snail, a cable 45 extending from the fork to the snail, a shaft on which the snail is mounted, a driving wheel mounted loosely on the shaft and operatively connected to one of the vehicle wheels, manually operable means for clutching said wheel to the snail shaft, and means 50 operable on lifting movement of the fork for automatically unclutching said wheel.

4. In loading apparatus, a wheeled vehicle, a fork pivoted at the front of the vehicle, a peripherally grooved snail, a shaft 55 carrying the same, a cable connecting the fork to the snail, a sprocket wheel mounted loosely on the shaft, the hubs of the sprocket wheel and snail being provided with clutch teeth, a sprocket wheel receiving motion 60 from the rear axle or wheel of the vehicle, a link belt connecting the sprocket wheels, a manually operable lever for shifting the sprocket wheel to effect clutching of the same to the snail, and means operable on 65 lifting movement of the fork for automatic-

ally moving the sprocket wheel from the snail.

5. In loading apparatus, a wheeled vehicle, a pivoted fork at the front of the vehicle, a pair of posts or standards carried by the frame of the machine, a cross tube connecting said posts or standards, a shaft extending through the tube, a pair of snails mounted on the shaft, cables connecting the snails to the fork, a sprocket wheel mounted 75 loosely on the shaft, the adjacent hub members of the sprocket wheel and one of the snails being provided with clutch teeth, a sprocket wheel driven from the rear wheel or axle, a link belt connecting the sprocket 80 wheels, a manually operable means for clutching the sprocket wheel to the snail, and means operable on lifting movement of the fork for automatically disconnecting the sprocket wheel and snail. 85

6. In loading apparatus, a wheeled vehicle, a pivoted fork at the front of the vehicle, a snail-carrying shaft, a pair of snails thereon, cables connecting the snails to the fork, a driven member loose on the shaft, 90 means for clutching said driven member to the shaft, said clutching means including a vertically disposed rock shaft, a crank arm at the lower end of the rock shaft, a pair of links extending from the crank arm, a manually operable lever connected to one of the links, and means carried by the fork and arranged to engage the other link for moving the clutching device to release position. 95

7. In loading apparatus, a wheeled vehicle, a pivoted fork at the front of the vehicle, a fork operating shaft, a driven member arranged to be clutched to the shaft and provided with a grooved hub, a shifting fork engaging said grooved hub, a rock shaft, an 100 arm extending therefrom and engaging said shifting fork, a crank arm at the lower end of the rock shaft, a link extending from the crank arm, a second link extending from the first and disposed transversely of the machine, a manually operable lever for actuating the links, and an arm carried by the fork and arranged to engage said second link to automatically unclutch the driven member when the fork assumes load dis- 110 charging position. 115

8. In loading apparatus, a wheeled vehicle, a pivoted fork, a fork actuating shaft, a braking device for the shaft, an operator's seat, and a brake operating lever mounted 120 at the rear of the seat in position to be engaged by the back of the operator.

9. In loading mechanism, a wheeled vehicle, a fork, a fork operating shaft, a friction drum mounted thereon, a band brake 125 encircling the drum, a vertically movable rod connected to one end of the band brake, a spring tending to elevate the rod and move the band to release position, a rock shaft, a crank arm arranged at one end of 130

the rock shaft and connected to the rod, an operator's seat, and an arm extending from the shaft and disposed to the rear of the operator's seat in position to be engaged by 5 the back of the operator.

10. In loading apparatus, a wheeled vehicle, a load receptacle, a fork pivoted in front of the machine and approximately the width of the receptacle, said fork having a support of contracted width, and an operator's seat arranged in front of the receptacle and directly to the rear of the main portion 10 of the fork so that the latter may swing to and fro over the seat.

11. In loading apparatus, a wheeled vehicle, a load receptacle thereon, a pivoted fork having a central support of less width than the fork proper, and an operator's seat arranged at the front of the receptacle and over which the fork may swing. 15

20 In testimony that I claim the foregoing as my own, I have hereto affixed my signature in the presence of two witnesses.

WILFRED BAKER.
